LAG FUSE

Gordon F. Laing, Delavan, Wis., assignor to Economy Fuse and Manufacturing Co., Chicago, Ill., a corporation of Illinois

Application April 16, 1953, Serial No. 382,602

10 Claims. (Cl. 200—123)

1

This invention relates to time lag fuses, and more especially to such fuses of the dual element type applicable to low amperage circuits, as, for example, ratings below three amperes, although it is not necessarily limited thereto.

In certain of its aspects, fuses of this invention follow the considerations of construction and operation presented in my contemporary United States Patent No. 2,543,245, issued on February 27, 1951, and No. 2,613,297, issued to me on October 7, 1952, respectively.

In the main, the present invention combines the positive-acting massive, relatively-movable, non-fusible heat storage elements of the latter patent, with an improved positive heater means assembly as disclosed in the former patent, for communicating heat to said heat storage elements.

There results from this an improved fuse which may be critically adapted to open circuit upon attainment of preselected current-time relationships without encountering objections of uncertainty and imprecision attributed to earlier embodiments, including those of the fusible type.

Other objects and advantages will become apparent hereinafter when the following description is read in conjunction with the accompanying drawings, in which—

Figure 1 is a mid-sectional plan view of a fuse construction in accordance with the present invention, shown with its parts in closed circuit position;

Figure 2 is a side elevational view of the device of Figure 1, shown partly in section, with the parts in open circuit position; and

Figure 3 is a modification of the heating unit employed in the foregoing embodiment.

Referring now to Figures 1 and 2, there is provided the usual insulator casing 10 of fiber or other suitable material, having metal cap terminals 12 and 14 which close the ends thereof, and at least one internal partition 16, which divides the interior of the casing into two chambers.

As viewed in Figures 1 and 2, the right hand chamber contains a fuse link 18 which extends from the terminal 14 to which it is soldered, through the partition 16, into the left hand chamber, where it is bent 90 degrees, and is staked to one of the massive electric conductors 20. The right hand chamber containing the fuse link 18 is preferably filled with quenching power 19 in the usual way.

A metal plunger element 22 is arranged in 55 form of the invention. Here the wire coil is re-

2

telescoping relation with the conductor 20 and is adapted to reciprocate back and forth with respect thereto so as to extend over to a metallic sleeve 24, to which it is secured by means 5 of solder 26, preferably of a eutectic alloy of predetermined melting point.

A resistance wire or heater coil 28 is soldered to the terminal cap 12 at its outer end and is soldered to the plunger 22 at the point where its 10 terminal convolution passes through an aperture in the metallic sleeve 24 provided therefor. All of these parts are soldered to the plunger so as to provide a union that is efficient in transmitting both electrical energy and mechanical 15 energy expressed as heat.

Concentrically arranged between the coil 28 and the metallic sleeve 24 is an insulating lining 30, which is of material, such as porcelain, that is capable of conducting heat while at the same 20 time is an insulator to electricity. The liner 30 electrically isolates the coil 28 from the metallic sleeve 24 to prevent the coil from becoming short-circuited, and also spaces the sleeve from the terminal 12 by a projecting end portion 32 provided for this purpose.

With the parts in closed circuit position, the plunger 22 is held in engagement with the metallic sleeve 24 by the eutectic alloy solder placed at points 26 and 27 against the bias of a tension spring 34 which tends to urge the plunger away 30 from the metallic sleeve 24 and into open circuit position, as shown in Figure 2.

Where a surge of current passes through the fuse that exceeds the capacity of the fuse link 18, the latter is adapted instantaneously to 35 blow out. On the other hand, where the overload is of a magnitude which can be immediately tolerated, but is greater than the intended circuit capacity over prolonged periods of time, and is less than will cause instantaneous failure of the fuse link 18, the current passing through the wire coil 28 gradually heats the latter. The heat in the coil is communicated through the porcelain lining 30 to the metallic sleeve 24, where it is collected and transmitted 40 to the plunger and associated parts until the temperature thereof exceeds the melting point of the eutectic solder.

At such point, the plunger 22 is released and 50 the spring 34 causes it to retract from the metallic sleeve 24 into the massive metallic member 20, to open the circuit. In this relationship, the parts appear as shown in Figure 2.

In Figure 3, there is illustrated a modified

placed by a wire 38 of higher resistance, inasmuch as it is straight and thus offers a shorter path of flow to the current than in the case of the coil 28. The metallic sleeve 40 may be made tubular in form without regard to cupping or flaring the ends, except for the flange 42, which is soldered to the plunger 22 in a manner similar to that previously described.

It is preferred that the resistance wire 38 be accommodated in a recessed portion 44 in the head of the plunger 22 so as to afford maximum contact with the latter, after passing through which the end of the wire projects through an opening in the sleeve as at 46, similar to the construction previously described.

All of these parts are soldered together. The wire 38 joins the terminal 12 with the plunger, but is electrically isolated from the sleeve 40 by the heat conducting, electrically-insulating liner 48, which abuts against the plunger at one end, but which projects sufficiently beyond the sleeve at its other end to maintain clearance between the terminal 12 and the end of the sleeve, as is indicated at 50.

This modified embodiment of heater is applied to the other parts as shown in Figures 1 and 2 in the manner and for the purpose previously described, whereby it is unnecessary to repeat the description pertaining thereto.

Fuses constructed in accordance with the present invention have the advantage of affording a positive source of heat from the heater unit which may be made effectively to control the operating conditions and periods of time in which the lag elements will be activated to open circuit position.

The heat generated in the heater unit upon overload is efficiently collected and transmitted to the massive members 20 and 22, which are adapted to store predetermined amounts of sensible heat before the temperature of all of the parts attains the fusion point of the eutectic alloy solder.

Great accuracy of performance and precision of control of circuit conditions are thus realized, which have not heretofore been possible in functionally similar fuse constructions known to the prior art.

I claim:

1. A lag fuse construction comprising a pair of terminals, a heater connected to one terminal, a fuse link secured to the other terminal, a pair of massive relatively movable heat and electric current conductors, a spring associated with

said conductors, fusible material holding said conductors in expanded condition against the bias of said spring in bridging relation between said heater and fuse link, said heater comprising a resistance wire extending between the adjacent terminal and conductor, a non-metallic heat transmitting envelope for said wire, and means in surrounding relation to said envelope for collecting and transmitting heat resident in said envelope to said adjacent conductor.

2. The invention of claim 1, in which said resistance wire is in the form of a coil.

3. The invention of claim 1, in which said envelope is an electrical insulator.

4. The invention of claim 1, in which said envelope is porcelain.

5. The invention of claim 1, said collecting means comprising a metallic sleeve of high heat conductive properties.

6. A lag fuse comprising a pair of terminals, a fuse link connected to one terminal, a heater link connected to the other terminal, a spring actuated plunger extending between said links and connected to one of them by fusible material, said heater link comprising a resistance wire extending between the terminal and plunger, a heat conductive ceramic sleeve surrounding said wire, and a metallic envelope enclosing said sleeve in electrically insulated relation to said terminal and wire detachably joined to said plunger in heat transmitting contact with the latter and with said ceramic sleeve.

7. The invention according to claim 6, in which the detachable joint between said envelope and plunger is comprised of a eutectic solder of predetermined low melting point.

8. The invention according to claim 7, said resistance wire being in the form of a coil coaxially disposed in said sleeve and envelope.

9. The invention according to claim 8, said fuse link being permanently electrically connected to said plunger.

10. The invention according to claim 9, said ceramic sleeve being of a porcelain-like material which is an insulator for electricity and conductor of heat.
